CLAIM

The ornamental design for a liquid-cooled integrated cabinet as shown and described.

DESCRIPTION

FIG. 1 is a top left front perspective view of a liquid-cooled integrated cabinet showing our new design;

FIG. 2 is a top right front perspective view of a liquid-cooled integrated cabinet showing our new design;

FIG. 3 is a bottom left front perspective view of a liquid-cooled integrated cabinet showing our new design;

FIG. 4 is a bottom right front perspective view of a liquid-cooled integrated cabinet showing our new design;

FIG. 5 is a front view of the liquid-cooled integrated cabinet showing our new design;

FIG. 6 is a rear view of the liquid-cooled integrated cabinet of FIG. 5;

FIG. 7 is a left side view of the liquid-cooled integrated cabinet of FIG. 5;

FIG. 8 is a right side view of the liquid-cooled integrated cabinet of FIG. 5;

FIG. 9 is a top view of the liquid-cooled integrated cabinet of FIG. 5;

FIG. 10 is a bottom view of the liquid-cooled integrated cabinet of FIG. 5;

FIG. 11 is an enlarged view of an encircled portion 11 of FIG. 1;

FIG. 12 is an enlarged view of an encircled portion 12 of FIG. 1;

FIG. 13 is an enlarged view of an encircled portion 13 of FIG. 1;

FIG. 14 is an enlarged view of an encircled portion 14 of FIG. 1;

FIG. 15 is an enlarged view of an encircled portion 15 of FIG. 1;

FIG. 16 is an enlarged view of an encircled portion 16 of FIG. 1;

FIG. 17 is an enlarged view of an encircled portion 17 of FIG. 1; and,

FIG. 18 is an enlarged view of an encircled portion 18 of FIG. 4.

The broken lines depict portions of the liquid-cooled integrated cabinet in which the design is embodied that form no part of the claimed design.

(Continued)

The long-dash short-dash broken lines indicate the portion of the enlarged views shown in the disclosure and form no part of the claimed design.
